UNITED STATES PATENT OFFICE.

THEODORE P. BROWN, OF WORCESTER, MASSACHUSETTS, ASSIGNOR TO SIMPLEX PIANO
PLAYER CO., OF WORCESTER, MASSACHUSETTS, A CORPORATION OF MASSACHU-
SETTS.

KEYLESS PIANO.

948,984.

Specification of Letters Patent.

Patented Feb. 8, 1910.

Application filed February 9, 1909. Serial No. 476,896.

To all whom it may concern:

Be it known that I, THEODORE P. BROWN, a citizen of the United States, residing at Worcester, in the county of Worcester and State of Massachusetts, have invented a new and useful Keyless Piano, of which the following is a specification.

This invention relates to a pneumatic musical instrument.

10 The principal objects of the invention are to provide a simple, practicable, and neat arrangement whereby a piano adapted to be controlled by an operator can be made without a key-bed or keys, or any levers constituting a substitute therefor; to provide a piano of the upright type adapted for automatic playing with a much less expensive construction than is necessary when an entire key-bed is employed; also to provide 15 a casing for such a keyless piano having a neat and attractive appearance and having provision for the tracker without greatly modifying the form of the ordinary upright casing.

20 Further objects and advantages of the invention will appear hereinafter.

Reference is to be had to the accompanying drawings, in which—

Figure 1 is a front elevation of one embodiment of the invention; Fig. 2 is a sectional view of the front portion of the same, on the line 2—2 of Fig. 1; Fig. 3 is a central vertical transverse sectional view; Fig. 4 is an end elevation of a wippen and connected parts; Fig. 5 is a plan of the wippen; Fig. 6 is an enlarged transverse sectional view of certain features; and Fig. 7 is a plan of a detail.

Heretofore in the construction of player, 40 or combination, pianos for automatic operation under the control of an operator, it generally has been customary to consider it desirable to be able to conceal the fact that the instrument was capable of automatic playing, and to make the casing as near as possible like an ordinary instrument for manual operation. This invention has for one object to produce an improved instrument designed to be personally controlled 45 during operation, which shall be frankly an automatic instrument, and which can be sold on the market at a much lower expense than even the cheaper makes of player pianos and yet be constructed in a superior manner and having every advantage which player pianos

have except the possibility of manual operation. With these things in view the ordinary key-bed, keys, and all forms of levers which would constitute a substitute for the keys are entirely eliminated. In place of the key-bed the instrument preferably is provided with a projection at the front for a longitudinal tracker so that the mechanism within the casing does not have to be contracted and displaced in order to provide a place for the latter. The striking pneumatics are located behind the tracker preferably and directly connected with the wippens which operate the hammers, in such a way that all motions of the hammers are positively transmitted to the movable leaves of the striking pneumatics so that when the hammers are held nearer the strings when ready to strike, the pneumatics will be partially incapacitated for causing the hammers to move with full striking effect. The expression manipulatory devices can conveniently come in under the tracker and extend up in front of it so as to be in position for efficient operation. The wind inducing devices are located in the bottom of the case where there is plenty of room and any type of pedals or panels can be employed either folding or otherwise.

Referring particularly to the drawings it will be seen that the invention is illustrated as in the form of an instrument of the upright type. The casing 10 of this instrument is shown as having a top portion or panel 11 which may be made in any ordinary form. This panel preferably is located all in one plane and below its ends are two side panels 12 also substantially in the plane of the top panel so that these three parts of the casing are substantially continuous with each other and may be made in any fancy woods or ornamented in any desired way so as to get the desired effects as to the appearance of the instrument.

About at the center of the front of the instrument is a hollow projection 13 constituting a tracker box and preferably supported by legs 14 extending from the bottom of the casing. Below this is shown a front panel 15 for folding pedals 16. Any desired type of pedals can be employed. These pedals are connected with the wind inducing devices 17 in any usual or desired manner.

The main wind chest 18 is shown connected with the wind inducing devices and with

exhaust channels in a series of primary valve boxes 19 which have chambers connected by tubes having bleeding passages with the exhaust channels, and communicating with tubes or channels 20 leading to a longitudinal inclined tracker 21 which is located within the tracker box, and is provided with a music spool and take-up spool 22 and 23 respectively. By locating the tracker along the front of the casing in inclined position, it takes up very little room, does not necessitate a large unsightly angular projection but permits the use of a small one 13 which can have a form similar to that of an ordinary key bed. The valve boxes 19 also communicate with tubes or channels 24 leading to secondary pneumatics 240 for controlling the striking pneumatics 25, each of which is connected by a vertical rod 26 directly with a wippen 27 which operates a hammer 28 in any usual or desired manner. The wind chest 18 communicates with the striking pneumatics through a conduit or chimney 250. In order to provide a simple and convenient connection between the rods 26 and the wippens 27, adapted to cause the movable leaves 29 of the pneumatics to move positively with the hammers as well as cause the hammers to move with the movable leaves and so that the rods can be disconnected readily from the wippens when it is desired to repair or remove any one or all of the striking pneumatics, the wippens are provided with open-ended slots 30, preferably lined with felt 31. The rods are detachably connected through these slots by means of nuts 32 both above and below and are connected with the movable leaves 29 of the striking pneumatics similarly by upper and lower nuts. The rods bear against a movable bar 33 which holds them in operative position, but as the rods and bar are at the front and the upper ends of the rods are connected so as to be detachable by a forward movement, when the bar is removed or pulled forward all the rods can be disconnected from the wippens very easily so that the striking pneumatics or any of them can be taken out or repaired from the front. This shows an important advantage of having the free ends of the wippens and movable leaves of the striking pneumatics at the front and substantially in vertical alignment with each other. The bar 33 is conveniently held in position by plates 34 each having an open ended slot 35 for a headed fastening 36 on the bar.

The hammers are shown as adjusted toward the strings to modulate the tone by means of a pivot' hammer rest rail 37 adapted to be operated by mechanism 38 under the control of a lever 39. On account of the positive connection of the rods 26 with the movable leaves of the pneumatics and with the wippens, and the adjustment

of the action to prevent lost motion the operation of the lever 39 not only moves the rest rail and chambers toward the strings to shorten the stroke, but this motion of the hammers pulls on the bridles, bridle wires, 70 wippens, and partially collapses the striking pneumatics, which prevents their actuating the hammers with full striking effect. Therefore the effect of the striking pneumatics will not be partly expended in neutralizing the effect of the adjustment of the hammer rest rail but both effects will co-operate to produce the desired result so that the rest rail does not have to be moved so near the strings for any desired modulating 80 effect and the pianissimo effects are clear and distinct. 75

The projection 13 provides a convenient location for the lever 39 and any other expression manipulatory devices which preferably are located in the tracker-box in front of the tracker and below it. 85

The instrument is shown as of the type involving primary and secondary pneumatics, the former located immediately below the 90 striking pneumatics and separate therefrom, and the latter on the striking pneumatics, but it will be understood that the single valve or any equivalent system can be used with the other features of this invention. 95

It will be seen that by means of this invention an instrument case is provided which, without departing widely from the accepted ideas as to the proper form of an upright piano, yet gives a distinctive appearance to the instrument and shows at once that it is an automatic and not a manual instrument, and yet distinguishing it from the "coin in the slot" machines which are of an entirely different class as they have no means for personal regulation or control and no pedals or bellows operated thereby. At the same time a space within the casing is left free for the usual devices with which manually operated pianos are provided, and the space ordinarily occupied by the rear portions of the key-levers, and the rods which extend up from them is utilized for placing the striking pneumatics. In this way an exceedingly compact and neat instrument is secured which is comparatively inexpensive in construction, and can be made to any desired degree of perfection and the striking pneumatics and their connections are so placed as to be readily accessible and easily removable, while the method of securing the pianissimo effects is very efficient as has been explained. 100 110 115 120

While I have illustrated and described a preferred embodiment of the invention, I 125 am aware that many modifications can be made therein by any person skilled in the art without departing from the scope of the invention as expressed in the claims. Therefore I do not wish to be limited to all the 130

details of construction shown and described, but

What I do claim is:—

1. In a pneumatic piano, the combination of an upright casing, hammers and wippens therein, said wippens being pivoted near the back of the casing and having their free ends near the front thereof, striking pneumatics located directly under said wippens and each having a movable leaf with the forward end free and directly under the free end of a wippen, and vertical rods connecting the free ends of said wippens and movable leaves, said rods being located in front of the striking pneumatics.
2. In a pneumatic piano, the combination of an upright casing, hammers and wippens therein, said wippens being pivoted near the back of the casing and having their free ends near the front thereof, striking pneumatics located directly under said wippens and each having a movable leaf with the forward end free and under the free end of a wippen, and vertical rods connecting the free ends of said wippens and movable leaves, said rods being readily detachable from the wippens.
3. In a pneumatic piano, the combination of an upright casing, hammers and wippens therein, said wippens being pivoted near the back of the casing and having their free ends near the front thereof, striking pneumatics located directly under said wippens and each having a movable leaf with the forward end free under the free end of a wippen, vertical rods connecting the free ends of said wippens and movable leaves, a movable bar extending across the casing in front of and in contact with said rods, and means whereby the upper ends of said rods will swing forward away from the wippens when the bar is moved forward.
4. In a pneumatic piano, the combination of an upright casing, hammers and wippens therein, said wippens being pivoted near the back of the casing and having their free ends near the front thereof, striking pneumatics located directly under said wippens and each having a movable leaf with the forward end free and under the free end of a wippen, vertical rods connecting the free ends of said wippens and movable leaves, said wippens each having an open ended slot in its end for receiving a rod, whereby the rods can swing out from the wippens, and means for holding the rods in position in said slots.
5. In a pneumatic piano, the combination of an upright casing, hammers and wippens therein, said wippens being pivoted near the back of the casing and having their free ends near the front thereof, striking pneumatics located directly under said wippens and each having a movable leaf with the forward end free and under the free end of a wippen, vertical rods connecting the free ends of said wippens and movable leaves, said rods being readily detachable from the wippens, valve boxes for controlling the striking pneumatics located under the striking pneumatics.
6. In a pneumatic piano, the combination of an upright casing, hammers and wippens therein, said wippens being pivoted near the back of the casing and having their free ends near the front thereof, striking pneumatics located directly under said wippens and each having a movable leaf with the forward end free and under the free end of a wippen, vertical rods connecting the free ends of said wippens and movable leaves, said rods being readily detachable from the wippens, valve boxes for controlling the striking pneumatics located under the striking pneumatics, a tracker located in front of the striking pneumatics and extending longitudinally of the casing, and connections extending rearwardly from the tracker to said valve boxes.
7. In a piano, the combination of an upright casing having a fixed projection near the center thereof and provided with a front portion, all substantially in the same plane, at the sides and top of said projection, hammers and wippens located within the casing at a higher level than said projection, striking pneumatics therefor located in the casing directly behind said projection under the wippens, and a tracker located in said projection and connected with said pneumatics.
8. In a piano, the combination of an upright casing having a top portion and portions continuous therewith at the sides all substantially in the same plane, and having a projection near the center thereof, of a tracker located within said projection, and striking pneumatics located directly behind the tracker in said casing and connected with the tracker.
9. In a piano, the combination of an upright casing, wind-inducing devices located in the lower portion thereof, striking pneumatics located above the wind inducing devices in the casing, hammers and wippens located directly above and connected with the striking pneumatics, and a longitudinal tracker projecting from the front of the casing near the center thereof.
10. In a piano, the combination of an upright casing, wind inducing devices located in the lower portion thereof, striking pneumatics located above the wind inducing devices in the casing, hammers and wippens located directly above and connected with the striking pneumatics, and an inclined longitudinal tracker projecting from the front of the casing near the center, said casing having a projection extending forwardly near its center and covering said tracker.
11. In a piano, the combination of an upright casing, wind inducing devices located

in the lower portion thereof, striking pneumatics located above the wind inducing devices in the casing, hammers and wippens located directly above and connected with the striking pneumatics, a tracker projecting from the front of the casing near the center, said casing having a projection extending forwardly near its center and covering said tracker, and expression manipulatory devices located within said projection and in front of the tracker.

12. In a pneumatic piano, the combination of a casing, striking pneumatics located near the center thereof, a tracker located in front of said striking pneumatics, a tracker box surrounding the tracker and projecting from the front of the casing, and expression manipulatory devices located within said tracker box.

13. In a pneumatic piano, the combination of the casing, striking pneumatics located near the center thereof, a tracker located in front of the striking pneumatics, a tracker box containing the tracker and projecting from the front of the casing near the center thereof, a lever in the forward part of said tracker box, a movable hammer rest-rail above the striking pneumatics, and means for connecting the lever with the hammer rest-rail for moving it.

14. In a piano, the combination of a casing, wind-inducing devices in the bottom

thereof, pedals extending from the front of the casing for operating the wind-inducing devices, striking pneumatics located above the wind-inducing devices and communicating therewith, primary pneumatics located between the wind-inducing devices and the striking pneumatics and communicating with both, secondary pneumatics communicating with the primary pneumatics and striking pneumatics, each located above its striking pneumatic, and a tracker in front of the striking pneumatics and connected with the primary pneumatics.

15. In a piano, the combination of a casing, wind-inducing devices in the bottom thereof, pedals extending from the front of the casing for operating the wind-inducing devices, striking pneumatics located above the wind-inducing devices and communicating therewith, primary pneumatics, secondary pneumatics communicating with the primary pneumatics and striking pneumatics, and a tracker in front of the striking pneumatics and connected with the primary pneumatics.

In testimony whereof I have hereunto set my hand, in the presence of two subscribing witnesses.

THEODORE P. BROWN.
